CLAIM

The ornamental design for a barrel opening cover, as shown and described.

DESCRIPTION

FIG. 1 illustrates a top plan view of a barrel opening cover showing our new and ornamental design;
 FIG. 2 illustrates a bottom plan view thereof;
 FIG. 3 illustrates a top perspective view thereof; and,
 FIG. 4 illustrates a bottom perspective view thereof.
 The broken lines in the drawings show environment and form no part of the claimed design.

1 Claim, 4 Drawing Sheets(56)
